UNITED STATES PATENT OFFICE.

HARRY C. BUHOUP, OF CHICAGO, ILLINOIS, ASSIGNOR TO THE McCONWAY & TORLEY COMPANY, OF PITTSBURGH, PENNSYLVANIA, A CORPORATION OF PENNSYLVANIA.

DRAFT APPLIANCE FOR RAILWAY-CARS.

1,361,440.

Specification of Letters Patent.

Patented Dec. 7, 1920.

Application filed June 3, 1920. Serial No. 386,350.

To all whom it may concern:

Be it known that I, HARRY C. BUHOUP, a citizen of the United States, residing at Chicago, in the county of Cook and State of Illinois, have invented certain new and useful Improvements in Draft Appliances for Railway-Cars; and I do hereby declare the following to be a full, clear, and exact description of the invention, such as will enable others skilled in the art to which it applies to make and use the same.

My invention relates to draft appliances for railway cars and is especially designed to afford strong, durable and simple means for permitting a car coupler to be attached to a draft yoke in a manner enabling the coupler to swing laterally when the car to which it is attached passes around a curve. The primary object of the invention is to afford a construction of the character indicated in which the coupler is detachably connected to the yoke in a manner rendering it capable of ready and easy removal and replacement in the event it is damaged or broken.

The principal feature of the invention, generally stated, consists in detachably connecting the coupler and yoke through the instrumentality of a key which is mounted on the yoke so as to be slidable downwardly in a direction oblique to the horizontal. A further feature of the invention consists in employing a removable bearing member as a portion of the means for detachably connecting the coupler and yoke, said bearing member being adapted to coöperate with the obliquely slidable key and being retained by the latter in assembled position.

In the drawings illustrating preferred embodiments of the invention, the scope whereof is pointed out in the claims,

Figure 1 is a plan view of a draft appliance embodying my invention, the forward end of the car coupler being broken away and portions of the yoke being omitted.

Fig. 2 is a side elevation of the construction shown in Fig. 1.

Fig. 3 is a detail vertical section on the line 3—3, Fig. 2.

Fig. 4 is a detail vertical section on the line 4—4, Fig. 1.

Fig. 5 is a detail sectional view on the line 5—5, Fig. 2.

Fig. 6 is a detail sectional view on the line 6—6, Fig. 2.

Fig. 7 is a view partly in plan and partly in section of a modified form of draft appliance embodying my invention, the forward end of the coupler and the rear end of the yoke being omitted.

Fig. 8 is a side elevation of the construction shown in Fig. 7, the draft yoke being in section.

Fig. 9 is a section on the line 9—9, Fig. 8.

In the construction illustrated in Figs. 1 to 6 of the drawings the connected draft members are a car coupler 1 and a draft yoke 2.

The yoke is provided with parallel arms 3 which are united at their rear ends by a transversely extending portion 4, and

it is also illustrated as provided with a transversely extending bridge or thimble

5 such as is employed when two sets of cushioning units (not shown) are installed

in the yoke to form what is known as a tandem draft rigging. The arms 3 of the yoke

are integrally united at their forward ends by a hood 6 which is formed with a forwardly opening socket 7 adapted to receive

the rear end of the stem of the coupler 1.

The socket 7 in the hood is preferably separated from the space between the yoke arms

3 for receiving the forward cushioning unit by a transversely extending wall 8 which integrally unites the yoke arms and is adapted

to engage the forward end of the cushioning unit. Where the draft member or coupler 1

is pivotally connected to the yoke the forward face 9 of the transverse wall 8 is prefer-

ably curved cylindrically to afford an ex-

tended bearing for receiving the buffing

shocks that may be transmitted to the coupler in any position which the latter may

assume in service.

The yoke is fashioned at its forward end

within the hood 6 with a rearwardly facing

shoulder or bearing 10 which, like the buffing

face 9 of the yoke, may be cylindrically

curved when the coupler 1 is designed to

swing laterally. Within the hood and sup-

ported on the lower wall thereof, in spaced

relation to the curved bearing shoulder 10 is

a removable bearing member 11 having a rearwardly facing preferably cylindrically

curved bearing shoulder or face 12 which is

adapted to coöperate with a correspondingly

formed shoulder or projection with which

the stem of the coupler 1 is provided at its

rear end. The removable bearing member

is also formed at the base of the curved bear-

- ing face 12 with a shelf 13 which extends rearwardly so as to engage the transverse wall 8 of the yoke and which furnishes a support for the rear end of the draft member 1.
- 5 The forward end of the member 11 is provided with an overhanging wedge shaped portion 14 affording a shoulder 15 for the engagement of a key 16 which is mounted in the lower portion of the hood 6 so as to be
- 10 slidable in a direction oblique to the horizontal and vertical.

The forward end of the yoke has a key receiving recess 17 which extends obliquely to the horizontal and vertical and intersects the forwardly opening socket 7 of the hood 6. The key way 17 is open at its lower end to permit the removal of the key 16 which is slidably mounted therein; and in order to provide for the use of simple means for 15 maintaining the key in assembled position as well as to enable it to be driven out of the key way should it become jammed therein, the said key way 17 is preferably open at its upper end also. To maintain the key in 20 assembled position it is preferred to employ a locking bar or rod 18 which extends through the key 16 from end to end and is capable of freely rotating with respect thereto, the said locking bar having its ends 19 bent so as to maintain its connection with 25 the key and also to cause it to have a bias to move under the influence of gravity to a position in which its ends or arms 19 overlap the side walls of the hooded portion of the 30 yoke, thus preventing movement of the key in the key way.

The stem of the coupler 1 is formed at its rear end with oppositely disposed projections which are adapted respectively to engage 40 the bearing shoulder 10 formed integral with the yoke and the bearing shoulder 12 of the removable member 11. These bearing shoulders of the coupler are preferably constituted by cylindrical trunnions 20 whose curvature corresponds to that of the bearing faces 9, 10 and 12 with which they engage.

The modified form of construction illustrated in Figs. 7, 8 and 9 is identical with 50 that illustrated in the other figures of the drawings and heretofore described except that the stem of the coupler 21 is connected to the yoke 2 through the intervention of a draft member 22 and a key 23 which extends 55 through said coupler stem and draft member. The features of construction which are alike in both forms of my invention have been indicated by corresponding reference numerals.

60 The draft member 22 is provided at its rear end with oppositely disposed cylindrical trunnions 20 which are adapted to cooperate with the correspondingly curved bearings 9, 10 and 12, and at its forward end 65 is preferably fashioned with slotted arms 24

between which the rear end of the stem of the coupler 21 is adapted to be received. The inner ends of the arms 24 are preferably united by transversely extending webs 25 so as to form a socket for receiving the rear end 70 of the coupler stem; and said draft member 22 is also preferably provided with a face 26 which engages the rear end of the coupler stem and receives the buffing shocks communicated from the coupler.

In assembling the structure illustrated in Figs. 1 to 6, inclusive, the rear end of the stem of the coupler 1 is inserted in the hood 6 and is then elevated until its upper trunnion 20 is in assembled relation with the 80 curved bearing face 10 of the yoke. The removable bearing member 11 is then inserted in the socket of the hood and pushed rearwardly therein beneath the coupler until its bearing face 12 engaged the lower trunnion 85 20 on the coupler stem. The key 16 is then inserted in the key way 17 in front of the shoulder 15 of the removable bearing member, thus preventing forward movement of the latter and thereby completing the attachment of the coupler to the yoke. When the key 16 is in assembled position the locking bar 18 is allowed to rotate until it is in locked position. With the exception that it is necessary to connect the draft members 21 and 22 by the key 24, the assembly of the modified form of my invention illustrated in Figs. 7, 8 and 9 is performed in the same way.

I claim:

1. In a railway draft appliance, the combination with a coupler, of a yoke, and means for detachably connecting said coupler and yoke, said connecting means involving a key mounted on said yoke so as to 105 be slidably transversely of the yoke and in a rectilinear direction oblique to the horizontal and vertical.

2. In a railway draft appliance, the combination with a yoke, of a draft member, and means for detachably connecting said draft member and yoke, said means involving a key which is downwardly movable transversely of the yoke and in a right line oblique to the horizontal to permit said 110 draft member to be detached from said yoke.

3. In a railway draft appliance, the combination with a yoke having a hooded forward end formed with a forwardly opening socket and provided with a key receiving 120 recess transversely intersecting said socket, of a removable bearing member, a draft member having a portion adapted to enter said socket, and means for detachably connecting said removable bearing member, 125 draft member and yoke, said means involving a key slidably mounted in said recess of the yoke and movable transversely of the yoke and downwardly in a rectilinear direction oblique to the horizontal to permit said 130

draft member to be withdrawn from said socket of the yoke.

4. In a railway draft appliance, the combination with a yoke having a hooded forward end formed with a forwardly opening socket and provided with a key receiving recess extending transversely of the yoke and obliquely to the horizontal and open at its lower end, of a removable bearing member, a draft member having a portion adapted to enter said socket, and means for detachably connecting said removable bearing member, draft member and yoke, said means involving a key slidably mounted in said obliquely and transversely extending recess of said yoke.

5. In a railway draft appliance, the combination with a yoke having a rearwardly facing bearing at its forward end and provided with a key receiving recess extending transversely of the yoke obliquely to the horizontal, said recess open at its lower end, of a removable bearing member having a bearing face spaced from said bearing of the yoke, said removable bearing member provided with an overhanging wedge shaped portion for the engagement of a transverse key, a draft member having oppositely disposed projections formed with

bearing faces one of which is adapted to engage the said bearing of the yoke and the other of which is adapted to engage the bearing face of said removable bearing member, and a rectilinear key slidably mounted in said transverse obliquely extending recess of said yoke and preventing removal of said removable bearing member.

6. In a railway draft appliance, the combination with a yoke having a rearwardly facing bearing and provided with a key receiving recess extending transversely of the yoke and obliquely to the horizontal, of a removable bearing member having a bearing face spaced vertically from said bearing of the yoke and provided with a wedge shaped over-hang for engagement with a transverse key, a draft member having oppositely disposed shoulders respectively adapted to engage said bearing of the yoke and said bearing face of the removable bearing member, a transversely extending key slidably mounted in said obliquely extending recess of said yoke and engaging said removable bearing member, and means for preventing accidental displacement of said key from assembled position.

In testimony whereof I affix my signature.

HARRY C. BUHOUP.
